CLAIM

The ornamental design for a combined table and tray for holding anesthesia and operating instruments, as shown.

DESCRIPTION

FIG. 1 is a right side elevational view of a combined table and tray for holding anesthesia and operating instruments, showing our new design;

FIG. 2 is a left side elevational view thereof;

FIG. 3 is a front elevational view thereof;

FIG. 4 is a rear elevational view thereof;

FIG. 5 is a top plan view thereof; and

FIG. 6 is a bottom plan view thereof.
